UNITED STATES PATENT OFFICE.

SHERMAN S. BENSON, OF YORK, NEBRASKA.

LAUNCHING APPARATUS FOR AERIAL TORPEDOES.

1,281,898.

Specification of Letters Patent. Patented Oct. 15, 1918.

Application filed January 29, 1918. Serial No. 214,356.

To all whom it may concern:

Be it known that I, SHERMAN S. BENSON, a citizen of the United States, residing at York, in the county of York and State of Nebraska, have invented a new and useful 5 Launching Apparatus for Aerial Torpedoes, of which the following is a specification.

This invention relates to apparatus for use in launching aerial torpedoes and is 10 primarily designed for launching bomb dropping machines such as disclosed in my co-pending application filed July 6, 1917, Serial Number 178,991, and in my co-pending application filed July 12, 1917, Serial 15 Number 180,184.

One of the objects of the invention is to provide mechanism to which the machines to be launched can be supplied readily and rapidly, the machines being carried upwardly and forwardly at a high speed and with their propelling mechanisms in operation so that, as the launching mechanism is disengaged from a machine, said machine will continue its flight in the selected 20 direction and under its own power.

A further object is to provide launching mechanism which is simple, durable and efficient and which is advantageous because it has rotary motion only.

With the foregoing and other objects in view which will appear as the description of the invention proceeds, the invention consists of certain novel details of construction and combinations of parts which will be 30 hereinafter more fully described and pointed out in the claim, it being understood that various changes may be made in the arrangement and proportions of the parts without departing from the spirit of the invention 35 as set forth in the appended claim.

In the accompanying drawings the preferred form of the invention has been shown. In said drawings—

Figure 1 is a side elevation of the launching apparatus in use.

Fig. 2 is an enlarged section on the dotted line in Fig. 1, looking in the direction of arrow 2.

Fig. 3 is an enlarged section on the same line but looking in the direction of the arrow 3, the clutch being shown partly in section.

Referring to the figures by characters of reference 1 designates a supporting structure provided with spaced parallel shafts 2 placed at different elevations and arranged

on each of these shafts are spaced sprockets 3. Endless chains 4 are mounted on the sprockets and the two chains are connected by cross bars 5 arranged in pairs and each of which has a pair of upwardly diverging horns 6. These horns are extended from short standards 7 which are spaced apart to provide a clearance 8 for the purpose herein-after pointed out.

The horns on each pair of bars 5 coöperate to form a cradle for supporting the body A of a bomb dropping machine from the rear end of which project tail planes B while a propeller G is provided at the front end. 70 The front horns of each pair are designated to be engaged by the body of the bomb dropper at the widest portion thereof and lugs 9 project from the body A and engage the horns to prevent the body A from slipping downwardly upon the cradle engaged thereby.

One of the shafts 2 has one member of a friction clutch fastened thereto, as shown at 10. A short drive shaft 11 aligns with the center of said clutch member and is adapted to be rotated at a high speed by a belt, not shown, driving a pulley 12, or in any other desired manner. A friction clutch member 13 is feathered on shaft 11 and is adapted to 80 be shifted by a lever 14 or the like, into or out of engagement with the clutch member 10 thus to couple or uncouple the two shafts.

In using the apparatus the machine to be launched is deposited on the lowermost 90 cradle. The clutch member 13 on the rapidly rotating shaft 11 is then shifted into engagement with the clutch member 10, thus to move the cradle upwardly at a gradually increasing speed. As the cradle with its 95 load reaches the uppermost portion of the inclined apparatus it will move downwardly and backwardly with the chains and be returned to its initial position. The propelling mechanism of the bomb dropper is 100 started before said machine is placed on its cradle. Consequently as soon as the propeller has attained a certain velocity the bomb dropper will move forwardly under its own power and withdraw from engagement with its cradle, this action being facilitated by the movement of the cradle which gives the bomb dropper its initial impulse. As shown in the drawings there is 105 sufficient room between the chains of the launching mechanism to permit the propeller to rotate and, by providing the clear-

ance 8 between the horns of each pair the tail planes can pass readily between the horns during the launching operation.

If desired two or more of the bomb drop-
5 pers may be positioned on the apparatus at one time, one being arranged in front of the other so as to be launched successively.

What is claimed is:—

The combination with a bomb dropper in-
10 cluding a body having a propeller at its front end and a tail plane, of launching mechanism including inclined endless chains, bars connecting the chains, spaced diverging horns on the bars and forming a cradle en-
15 gaging the body, means projecting from the body and engaging the fronts of the horns

to hold the body in position on the cradle, the chains of the launching mechanism being spaced apart to permit rotation of the propeller of the bomb dropper on the cradle, there being a clearance between the horns for the passage of the tail plane during the launching of the bomb dropper, and means for actuating the chains.

In testimony that I claim the foregoing as 25 my own, I have hereto affixed my signature in the presence of two witnesses.

SHERMAN S. BENSON.
